SPRING ASSEMBLY

Charles D. Karr, Holland, Mich.

Application February 4, 1935, Serial No. 4,755

5 Claims. (Cl. 5—267)

The invention relates to spring assemblies for mattresses, and which consist of spiral springs arranged side by side and connected together.

It is important that such spring assemblies should offer approximately uniform resistance to compression throughout the entire area; that this resistance should be suitably regulated; and that the spirals, while being attached together, should be capable of movement under compression without noise.

It is the object of this invention to secure these desirable qualities in a spring assembly, and at reasonable manufacturing cost.

The invention is fully hereinafter explained and is illustrated in the accompanying drawing, in which

Fig. 1 is a detail plan view of the improved spring assembly;

Fig. 2 is a detail section on the line 2—2 of Fig. 1; and

Fig. 3 is a perspective view of one of the links of a chain employed to secure a row of spirals together.

The spirals, as 10, 11, are preferably of the known hour glass type. In the drawing but one face of the assembly is shown, and consequently but one end of the spirals. These spirals are, as usual, arranged in straight rows which are normal to each other.

Such assemblies are usually oblong rectangular in form, and it is desirable that at least the longer margins, which would be regarded as the sides of the mattress in which the assembly is incorporated, shall be provided with a binder connecting the end spirals of adjacent cross rows together. In the present instance such binders are shown at 12, 13, and are in helical form. If desired binders may be applied to the end margins of the assembly. The objects of such binders especially as applied to the sides of the assembly are to strengthen the spring resistance to sustain the entire weight of a user when sitting upon the mattress; and to provide straightened edges for linear anchorage, in the process of upholstering.

For convenience the rows of spirals which unite the helicals 12, 13, will be referred to as the cross rows, and those which are parallel with these helicals as the longitudinal rows.

Adjacent spirals of each longitudinal row are coiled in the same direction, those of adjacent rows, however, and adjacent spirals of the cross rows being reversely coiled. All of the spirals of the assembly except certain of those in the end transverse rows have open end turns, as shown

in the spiral 11, and the terminal of such turn is formed into a hook, as shown at 14, which engages over the end turn of an adjacent spiral of the same longitudinal row. Alternate spirals at the ends of the longitudinal rows have their end turns closed, their terminals being engaged with the second turn of the spiral, as shown at 15.

The spirals of each transverse row are secured together by a continuous chain formed of V-shaped links 16, the apexes of adjacent links 10 being oppositely directed. The length of these links is slightly greater than the diameter of the end turns of the spirals, and their width is such that their apexes 17 extend approximately to such turn. At each end of the link the wire is formed into an eye, as 18, 19, the end of the wire being continued backwardly and taking the form of an open hook, as 20. In assembling the chain the eyes 18, 19, of adjacent links are interengaged and their hooks 20 extend backwardly over the 20 end turn of the spiral with which this individual link is associated. Preferably the end turn of the spiral is indented or distorted, at the points of attachment of the link, the indentation, as 21, extending axially as to the spiral. The planes 25 of the eyes 18, 19, are oblique to the plane of the body of the link, the planes of the two eyes of each link being similarly inclined.

In assembling the elements of the chain the eyes of adjacent links are interengaged and in 30 applying the chain to the spirals the hooks 20 are engaged with the indentations 21. The hooks 14 at the ends of the open spirals enclose not only the end turn of an adjacent spiral but also the link 16 at its apex.

In a spring assembly formed as described flexibility and firmness are both provided for and nicely balanced. The relative reverse winding and arrangement of the spirals, and the dual flexing action of the links of the chain, secure a 40 wide distribution of a load locally applied, while the form and arrangement of the links of the continuous connecting chains tend to restrain flexure.

Each of the links 16 is securely attached to the end turn of one of the spirals, and accidental disengagement is prevented by the securing of the link at its apex by the loop at the terminal of the final turn of an adjacent spiral. Disengagement of the eyes of adjacent links is impossible so long as the hooks remain engaged. An oblique formation of the eyes provides for ample swiveling movement and for unrestrained hinge action. The interlocking, however, of the 55

end turns of adjacent spirals of the transverse rows imposes a limit on this flexibility.

The improved spring assembly is noiseless, there being an entire absence of the objectionable clicking due to the snapping of one wire past another, for there are no wires so associated that any such action can occur. While the apexes of the links of the connecting chains are contiguous to the end turn of the spiral, the two always move together under load.

The parts are all simple of manufacture and assembly, and in addition to the saving of labor there is a saving of material as compared with the common type of spring assemblies in which helicals are used as connecting means.

The invention is of greater scope than the specific embodiment of it.

I claim as my invention:—

1. In a spring assembly for mattresses, in combination, a plurality of spirals arranged in rows, a chain of V-shaped links having their ends interlocked each link having its ends attached also to the terminal turns of one of the spirals and at diametrically opposite points, the apexes of adjacent links being oppositely directed and connected with the end of the terminal turn of a laterally adjacent spiral.

2. A spring assembly for mattresses comprising a plurality of spirals arranged in rows, a chain composed of V-shaped links each link having its ends attached to the terminal turn of a spiral at diametrically opposite points and interlocked with links of adjacent spirals of the same row, the apexes of the adjacent links being oppositely directed, the end of the terminal turn of each spiral of an inner row being interlocked with the terminal turn of a spiral of the next adjacent row and with the apex of the V-link associated therewith.

3. A spring assembly formed of spirals arranged in juxtaposed rows, adjacent spirals of

each row being reversely coiled and of contiguous rows being similarly coiled, the spirals of each row being connected by a continuous chain formed of V-shaped links each link having its ends in hooked engagement with the terminal turn of one of the spirals and at opposite portions thereof, and in eye engagement with the ends of links associated with adjacent spirals, the end of the terminal turn of each spiral being in looped engagement with the contiguous spiral of an adjacent row and with the apex of the link associated with such spiral.

4. A spring assembly comprising, in combination, a plurality of spirals each having an open end turn terminating in a hook and having diametrically opposite indentations ninety degrees from such hook, a V-shaped link formed of a single strand of wire associated with each spiral and having at each end an eye and a hook, the eyes of links associated with adjacent spirals being interlocked and the hooks of each link engaging in one of the indentations of the spiral with which such link is associated, the apex of the link being adjacent to the end turn of the spiral and being enclosed within the terminal hook of an adjacent spiral.

5. A spring assembly comprising in combination, spirals arranged in two sets of relatively normal rows, adjacent spirals of one set of rows being similarly coiled, and connected by the looping of the terminal of the end turn of one upon the end turn of the other, adjacent spirals of the other set of rows being reversely coiled and connected together by a chain formed of V-shaped links, the ends of each link being attached to the end turn of one of the spirals at diametrically opposite points and in line with the longitudinal axis of the row, and its apex being engaged with the end turn of a laterally adjacent spiral.

CHARLES D. KARR.
